UNITED STATES PATENT OFFICE.

DANIEL HOGAN, OF HOBOKEN, NEW JERSEY, ASSIGNOR TO MEINECKE & COMPANY, OF NEW YORK, N. Y., A CORPORATION OF NEW JERSEY.

1,169,101.

Specification of Letters Patent. Patented Jan. 18, 1916.

Application filed June 7, 1915. Serial No. 32,501.

To all whom it may concern:

Be it known that I, DANIEL HOGAN, a citizen of the United States, residing in Hoboken, county of Hudson, and State of New Jersey, have invented certain new and useful Improvements in Bed-Pans, of which the following is a specification.

My invention relates to a bed-pan, often called a douche-pan, and has for its object to provide a pan which shall be free from certain objections appertaining to pans of the prior art.

More particularly it is the object of my invention to provide a bed-pan which can be shifted or removed from under the user without liability to a slopping over of the contents so as to wet the person of the user or the bed clothing.

A further object of my invention is to provide a bed-pan which, while having only the usual area of base and the usual area of supporting surface for the buttocks and thighs, and while being sufficiently low to be readily slipped under the person of the user, will still have a very large cubic capacity.

A most important object of my invention is to provide a bed-pan which shall combine with all the usual good features of bed-pans, a much greater stability.

My improved bed-pan is so constructed that it is practically impossible to upset it accidentally. In bed-pans of the prior art the usual construction has embodied a lower body or containing portion having a broad upwardly and outwardly flared flange united to the upper edge of said body portion at its front and sides for the support of the thighs and buttocks. The side walls of the pan proper have usually been vertical or substantially vertical, and have extended directly downward from the inner contour line of the flange. As a consequence, any attempt on the part of the user to shift his position when using the bed-pan has resulted in an excess pressure on the overhanging flange, at one side or the other, and the upsetting of the pan. In my improved bed-pan the two side walls and the front end wall of the body portion are flared outwardly and downwardly away from the inner contour line of the flange to a base, of substantially the same size and contour as said flange, which is positioned immediately below the same. In this way, any excessive

pressure on one side or the other of the overhanging support is comparatively ineffective to tip the pan and spill its contents. My invention will be better understood by referring to the accompanying drawings in which—

Figure 1 represents a plan view of my improved bed-pan; Fig. 2 represents a side elevation thereof; Fig. 3 represents an end elevation taken from the front end (left) of Fig. 1; Fig. 4 represents a view of Fig. 1, taken from below; Figs. 5, 6 and 7 represent cross sections taken respectively along the lines 5—5, 6—6 and 7—7 of Fig. 1.

In the drawings the bed-pan comprises a main body or receptacle portion *a*, having an oval base *e*, and a thigh and buttock supporting portion *b* which flares upwardly and outwardly from the rim of the body portion except for a small portion at the rear end *c* thereof. The flared support *b* is of a substantial width at the front end *d* and also at the sides of the body portion of the pan, the width decreasing toward the rear until its outer contour finally merges with the outer contour of the body portion wall near the rear end. The angle of flare is so determined throughout that the support will conform to the thighs and buttocks so as to insure a maximum of comfort to the user.

The body portion is, as usual, substantially lower at its front end than at its rear, as is also the bed-pan, taken as a whole, thus permitting the ready insertion and removal of the pan under and from under the user. The rear end *c* of the pan slopes downwardly and inwardly but the sides and front end *d* of the body portion are flared downwardly and outwardly throughout that portion of the periphery of the pan corresponding to the flared support so as to unite with the oval base *e*. The outer edge of this base, except for the portion in the immediate vicinity of the rear end of the pan, has a contour substantially the same as the outer contour of the flared support and lies just within the vertical projection of such latter contour.

As a consequence of the construction above described, any downward pressure upon any portion of the flared thigh and buttock support is exerted upon points which either lie entirely within the margin of the base or so near to said margin that any tendency to tip the bed-pan as a whole is substantially ab-

sent. The flared thigh and buttock support affords a very convenient means for firmly grasping the bed-pan when it is necessary to insert the same under the user, or to remove it therefrom, as well as in moving the bed-pan from place to place. The outwardly convexed base portion gives the bed-pan a large cubic capacity. This convexed portion, which extends around nearly the entire bed-pan, also serves as a pocket which takes the surge of any contained fluid when the pan is suddenly moved and prevents the flowing of such fluid upon and over the surface of the flared thigh and buttock support. Despite the deep convexing of the body portion of the pan its entire inside wall is visible at all times and accessible so as to be readily cleaned. On account of its large base the bed-pan may be used upon an ordinary chair or stool as a commode.

Copies of this patent may be obtained for five cents each, by addressing the "Commissioner of Patents, Washington, D. C."

Having described my invention, I claim: A bed pan comprising a lower body portion and an upper thigh and buttock supporting portion, said body portion having a base, the outer edge of which is substantially in line with the outer edge of the thigh and buttock supporting portion, and having side and front walls extending inwardly and upwardly to the inner edge of said thigh and buttock supporting portion, and said thigh and buttock supporting portion being of a substantial width at the front and sides of the pan.

In testimony whereof I have hereunto set my hand in the presence of two subscribing witnesses.

DANIEL HOGAN.
